UNITED STATES PATENT OFFICE.

THOMAS E. MYKINS, OF ROCHESTER, NEW YORK.

AUTOMATIC STOP MECHANISM FOR SOUND-REPRODUCING MACHINES.

1,201,751

Specification of Letters Patent. Patented Oct. 17, 1916.

Application filed January 20, 1913, Serial No. 743,085. Renewed August 16, 1916. Serial No. 115,330.

To all whom it may concern:

Be it known that I, THOMAS E. MYKINS, of Rochester, in the county of Monroe and State of New York, have invented certain new and useful Improvements in Automatic Stop Mechanisms for Sound-Reproducing Machines; and I do hereby declare the following to be a full, clear, and exact description of the same, reference being had to the accompanying drawings, forming a part of this specification, and to the reference-numerals marked thereon.

My invention relates to improvements in automatic stop mechanisms for sound reproducing machines, and more particularly to the class of machines which are characterized by a rotatable table on which is supported a flat record adapted to be engaged by a needle arranged on a swinging arm, and it has for one of its objects to provide a mechanism by which the parts may be set in advance so as to automatically stop the movement of the rotatable table at a predetermined point, either at the middle or any other part of the record, and to make the device also susceptible of adjustment so as to stop the movement of the table at the end of records of different lengths.

A further object of my improvement consists in providing a construction and arrangement of parts so that the desired adjustment may be instantaneously made, and with little difficulty.

A still further purpose of my invention resides in providing a simple and inexpensive mechanism that may be readily applied to any type of flat record sound reproducing machine.

To these and other ends the invention consists in certain improvements and combinations of parts all as will be hereinafter more fully described, the novel features being pointed out in the claims at the end of the specification.

In the drawings: Figure 1 is a plan view of a flat record machine, with parts broken to show the application of a preferred embodiment of my invention; Fig. 2 is a sectional view on the line 2^a—2^a of Fig. 1; Fig. 3 is a sectional view on the line 3^a—3^a of Fig. 2; Fig. 4 is a vertical sectional view of a portion of the brake releasing device; Fig. 5 is a side elevation; Fig. 6 is a plan view, with a portion of the swinging arm broken away, showing the brake mechanism in engagement with the table; Fig. 7 is a

vertical sectional view of the brake mechanism; Fig. 8 is a transverse, vertical sectional view on the line 8^a—8^a of Fig. 7, and Fig. 9 is a similar view on the line 9^a—9^a of Fig. 7.

Similar reference characters throughout the several views indicate the same parts.

In the present embodiment of the invention, 1 designates the frame on which the parts are mounted and 2 is the rotatable table, which may be operated by any suitable motor as usual in this class of devices.

3 is the swinging arm which is pivotally mounted on the frame upon the post 4, held in position by the standard 5.

The brake mechanism is preferably arranged in a housing 6 which is attached to the frame in any convenient manner, as by means of a lug 7, secured to the plate 8 by means of a screw 9. The brake consists of a milled head 10, which is preferably provided with an inserted portion 11 of resilient material for engagement with the edge of the table and is adjustably supported on the rod 12 whereby the brake mechanism may be readily adapted to tables of different diameters. The rod 12 is slidably mounted in the housing 6, and is actuated normally in the direction of the rotating table by means of the spring 13.

14 is a lever pivoted in the housing upon the set screw 15, the lower end of said lever being in engagement with the aforementioned rod 12, while the upper end of the lever engages a rod 16 which is slidably mounted in the upper part of the housing and carries a finger piece in the form of a screw 17 which travels in a recess 18 and includes a head disposed beyond the side of the housing as shown in Fig. 8. The slidable rod 16 extends beyond the end of the housing, as appearing in Fig. 7, and co-operates with the brake releasing device in a manner which will presently be made clear.

The brake releasing device is mounted on the swinging arm 3, preferably in a manner to be adjustable, and in the present arrangement, it includes a split ring 19, the adjacent ends of which are held together by means of a bolt 20 and nut 21. The ring 19 carries a downwardly extending arm 22 upon which is arranged a laterally disposed curved guide 23 which includes upper and lower overhanging flanges 24.

25 designates a recess which extends longitudinally of the guide.

26 is a slidable member preferably in the form of a curved plate arranged on the guide 23 and held in proper relation thereto by means of the flanges 24. The member 26 is slidable in the guide, being provided at one end with the finger piece 27 and at its opposite end with the flange 28 arranged to engage one end of the guide so as to limit the inward movement of the slidable member. 10 The member 26 is also provided with a recess or opening 29 which is adapted to receive the end of the rod 16 of the brake mechanism, when the swinging arm is moved to such a position as to bring said recess into alignment with the said rod.

15 With this description of the construction, the operation will be readily apparent, and, briefly, is as follows: Normally the brake mechanism is in the position shown in Fig. 20 6, the brake being engaged with the rotatable table. A record having been placed on the table, the arm is moved until the needle is at the point where it is desired to stop the movement of the table. During this preliminary 25 adjustment of the arm, it will be noted that the rod 16 is engaged with the recess in the slidable member 26, thereby holding said slidable member, while the guide 23 moves relatively thereto with the swinging arm. 30 The finger piece 17 is then operated to disengage the brake from the table, which also causes the rod 16 to be withdrawn from engagement with the slidable member 26. The swinging arm is then set at the beginning of 35 the record, the sounds of which are reproduced until the arm has moved far enough to bring the recess of the member 26 into alignment with the rod 16, which then drops in the recess and permits the brake to be 40 forced against the table by the spring 13.

45 It will be obvious that the invention is not limited to the exact details of construction herein set forth, but comprehends any arrangement which may be characterized by a 50 brake mechanism adapted to be released by a coöperating part that can be laterally adjusted upon the swinging arm to any one of a series of different positions, and preferably a slidable member arranged on a supporting 55 guide.

50 I claim as my invention:

55 1. In a machine for reproducing sound, the combination with a rotatable table, of a swinging arm movable over the top of the table, a brake mechanism arranged to engage the table, and a brake releasing device arranged on the swinging arm for coöperation with the brake, said brake releasing device embodying a slidable member adjustable 60 laterally of the swinging arm and coöperating with the brake.

65 2. In a machine for reproducing sound, the combination with a rotatable table, of a swinging arm movable over the top of the table, a brake mechanism arranged to engage

the table, and a brake releasing device arranged on the swinging arm for coöperation with the brake, said brake releasing device embodying a guide, and a slidable member arranged on the guide and coöperating with 70 the brake.

3. In a machine for reproducing sound, the combination with a rotatable table, of a swinging arm movable over the top of the table, a brake mechanism arranged to engage 75 the table, and a brake releasing device arranged on the swinging arm for coöperation with the brake, said brake releasing device embodying a curved guide, and a curved slidable member arranged on the 80 guide and coöperating with the brake.

4. In a machine for reproducing sound, the combination with a rotatable table, of a swinging arm movable over the top of the table, a brake mechanism arranged to engage 85 the table, and a brake releasing device arranged on the swinging arm for coöperation with the brake, said brake releasing device embodying a curved guide, and a curved slidable member arranged on the guide and 90 provided with a recess which coöperates with a portion of the brake mechanism to release the same.

5. An automatic stop having, in combination, an oscillating-member provided with a 95 curved guide-way substantially concentric with its center of oscillation; a curved controlling-member supported in said guide-way and retained frictionally against longitudinal movement therein, said controlling-member having a recess; a brake; a spring 100 tending to throw the brake into operation; and a second controlling-member connected with the brake and normally seated against the surface of the curved controlling-member, whereby the brake is held out of operation, said second controlling-member having an extremity adapted to enter said recess to permit the brake to operate, and fitting the recess closely so as to retain the curved controlling-member against movement with the oscillating-member when the recess is so engaged.

6. An automatic stop having, in combination, an oscillating-member provided with 115 a guide plate arranged with its width vertical and curved concentrically with the center of oscillation, the guide-plate being provided with upper and lower marginal flanges; a sheet-metal cam-plate embraced 120 by said flanges and held thereby in curved position, the cam-plate being provided with a recess; a brake; a controlling-member connected with said brake and having an extremity engaging the forward surface of 125 the cam-plate and adapted to enter the recess therein; and a spring tending to throw said extremity into said recess and to move said member in a direction to throw the brake into operation.

7. An automatic stop having, in combination, an oscillating-member comprising a clamping-collar, an arm projecting forwardly and downwardly therefrom, and a 5 guide-plate carried by said arm, the guide-plate being arranged with its width vertical and curved concentrically with the axis of oscillation, and the guide-plate having a horizontal slot and upper and lower marginal rearwardly-bent flanges; a cam-plate supported by the guide-plate and retained by said flanges, the forward surface of the cam plate being accessible through said slot, 10
- and the cam-plate being provided with a recess; a brake; a slide-rod carrying the 15 brake and having an end adapted to engage the forward surface of the cam-plate and to enter the recess therein; and a spring tending to throw said extremity into said recess and to move the slide-rod in a direction to throw the brake into operation. 20
